UNITED STATES PATENT OFFICE.

MENOTTI PELLEGRINO, OF NEW YORK, N.Y.

COAL-EMPTIER.

1,212,252.

Specification of Letters Patent. Patented Jan. 16, 1917.

Application filed May 29, 1912. Serial No. 700,496.

To all whom it may concern:

Be it known that I, MENOTTI PELLEGRINO, a subject of the King of Italy, residing in the borough of the Bronx, city of New York, county of New York, State of New York, have invented new and useful Improvements in Coal-Emptiers, of which the following is a specification.

The object of my invention is to provide a novel construction of coal-emptying apparatus for coal-cars, which shall be reasonably simple in construction and thoroughly efficient in operation.

With this object in view, and others appearing as the specification proceeds, the invention resides in the novel construction, combination and arrangement of parts of a coal-car emptying apparatus as herein-after fully described in the specification, summed up in the claims, and illustrated in the drawing.

Briefly stated, the invention comprehends a structure in which automatically-operating, vertically-descendant spears or push-bars operate in conjunction with hammers knocking on the side of the car to be emptied, to loosen and remove the coal within the car. More specifically stated, the invention comprehends a novel mechanism, common to said push-bars and said hammers, for simultaneously operating them, which is a great advantage over actuating the hammers and the push-bars independently, *i. e.*, by mechanisms not inter-related.

The invention is graphically illustrated in the accompanying drawing, in which like reference-characters denote corresponding parts throughout the specification.

In this drawing: Figure 1 is an end view of a coal-car of the dumping species, equipped with my invention; Fig. 2 is a side elevation thereof; Fig. 3 is a partial transverse section on the line 3—3, Fig. 2; Fig. 4 is a top plan view; and Fig. 5 is a fragmentary, collective, detail view of the main shaft, with its crank and connections with the hammers.

Referring, now, in detail to the drawing: H designates a frame or box, in this instance rectangular and preferably constructed of steel, arranged to be disposed on top of the dump-car 2.

Mounted in bearings *a* on top of the frame H is a longitudinally-extending, rotatable shaft A, carrying rigidly a gear-wheel B and

loose and fixed pulleys *b*, *b'*, which may be connected, in the usual manner, with a suitable prime-mover, or source of power (not shown).

Meshing with the gear-wheel B is a pinion *b* fast on the end of a longitudinally-extending, rotatable shaft *c* mounted in bearings in the frame H, and carrying, at the opposite end, a fly-wheel *c'*. The shaft *c* also carries cranks D, to which are pivoted links *d*, pivoted to transversely-extending, horizontal, reciprocable rods *e*, projecting through bearings in the sides of the frame H, and carrying, at their outer ends, longitudinally-extending, horizontal shafts E, E, guided in brackets F, F, F, F, carried by the sides of the frame H, exteriorly thereof.

Hammers G are carried at the lower ends of depending hammer-rods *g*, pivoted, at their upper ends, as at *g'*, to the sides of the box H, near the top thereof. The hammer-rods *g* are provided with longitudinally-extending slots *g*², in which work pins *f* passing through the free ends of yokes or forks I, projecting from and carried by the shafts E, E.

Vertically-disposed spears or push-bars K project vertically through the frame or box H, and are provided, along one edge, with rack *k*, with which mesh operating-members, in this instance teeth *h'* (although, as is obvious, cog-wheels or pinions may be used instead), carried by the shaft *c*.

In operation, when it is desired to empty a car of coal, the box or frame H may be disposed or lowered upon the top of the dump-car 2 by any suitable mechanism (forming no part of my invention). The power is then connected up with the fixed pulley *b'*, which revolves the latter and, with it, the shaft A and the gear-wheel B. The gear-wheel, meshing with the pinion *b*, drives the latter, which, in turn, drives the shaft *c*. The revolution of the shaft *c*, through the medium of the cranks D and the links *d*, reciprocates the rods *e* back and forth, which movement of said rods, by reason of their connection with the hammer-rods *g*, rocks the latter back and forth on their pivots *g'*, ringing the hammers forcibly into contact with the sides of the car 2, thereby knocking the coal from the sides of the car. Simultaneously, the teeth *h'* are revolved, which, by reason of their engagement with the racks *k*, force the spears or

push-bars K downward through the coal in the car 2, thereby pushing the coal out of the bottom of the car.

From the above description, taken in connection with the drawing, the many advantages of my invention will be apparent, especially to those skilled in the art to which the invention appertains.

I am aware that many modifications in detail may be made; but all such changes as come within the scope of the appended claims constitute no departure from the spirit of the invention and fall within the purview thereof.

Having thus fully described my invention, what I claim as new and desire to secure by Letters Patent of the United States is:

1. In a coal emptier, upright push-bars adapted to be driven through the coal in a car to force the coal therefrom, hammers adapted to be knocked against the side of the car, and means, common to both the push-bars and the hammers, for simultaneously actuating them.

2. In a coal emptier, upright push-bars adapted to be driven through the coal in a car to force the coal therefrom, hammers adapted to be knocked against the side of the car, and power-driven means, common to both the push-bars and the hammers, for simultaneously actuating them.

3. In a coal emptier, upright push-bars adapted to be driven through the coal in a car to force the coal therefrom, hammers, carried by hammer-rods, adapted to be knocked against the side of the car, and means, common to both the push-bars and the hammers, for simultaneously actuating them, said means including: a rotatable

shaft, reciprocable rods, and mechanism connecting said shaft and rods, whereby movement of the former actuates the latter.

4. In a coal emptier, upright push-bars adapted to be driven through the coal in a car to force the coal therefrom, hammers, carried by hammer-rods, adapted to be knocked against the side of the car, and means, common to both the push-bars and the hammers, for simultaneously actuating them, said means including: a rotatable shaft, cranks carried by said shaft, reciprocable rods, and links connecting said shaft and rods.

5. In a coal-emptier, a box, upright push-bars projecting through said box, hammers adapted to be knocked against the sides of the car, hammer-rods carrying said hammers and pivoted to said box, and means, common to both the push-bars and the hammers, for actuating them simultaneously.

6. In a coal-emptier, a box, upright push-bars projecting therethrough, hammers adapted to be knocked against the sides of the car, hammer-rods carrying said hammers and pivoted to said box and means, common to the push-bars and the hammers, for simultaneously actuating them, said means including: a shaft, members carried by said shaft and engaging said push-bars to force the latter downward upon rotation of said shaft, and mechanism intermediate said shaft and said hammer-rods to actuate the latter upon movement of the former.

MENOTTI PELLEGRINO.
